Primary Examiner — Mark A Goodwin(74) *Attorney, Agent, or Firm* — Rickard K. DeMille; Rebecca L. Henkel(57) **CLAIM**

The ornamental design for a control assembly of an agricultural work vehicle, substantially as shown and described.

DESCRIPTION

FIG. 1 is a perspective view of a control assembly of an agricultural work vehicle showing our new design.

FIG. 2 is a top view thereof.

FIG. 3 is a left side view thereof.

FIG. 4 is an enlarged view taken along line 4-4 in FIG. 3 thereof; and,

FIG. 5 is a back view thereof.

Phantom lines, where utilized, are for illustrative purposes only and form no part of the claimed design.

1 Claim, 5 Drawing Sheets(56)
